US0D1025907S

(12) **United States Design Patent** (10) **Patent No.:** **US D1,025,907 S**
(45) **Date of Patent:** **** May 7, 2024**

(54) **WIRELESS CHARGER**

(71) Applicant: **Electronic Silk Road (Shenzhen) Tech Co., Ltd.**, Shenzhen (CN)
(72) Inventors: **Junwei Liu**, Guangdong (CN); **Yaohua Xie**, Guangdong (CN); **Weize Xu**, Guangdong (CN); **Meixia Lan**, Guangdong (CN)

(**) Term: **15 Years**

(21) Appl. No.: **35/516,120**

(22) Filed: **Dec. 29, 2022**

(80) **Hague Agreement Data**

Int. Filing Date: **Dec. 29, 2022**

Int. Reg. No.: **DM/226086**

Int. Reg. Date: **Dec. 29, 2022**

Int. Reg. Pub. Date: **Jan. 27, 2023**

CLAIM

The ornamental design for a wireless charger, as shown and described.

DESCRIPTION

1. Wireless charger

1.1 : Front

1.2 : Back

1.3 : Left

1.4 : Right

1.5 : Top

1.6 : Bottom

1.7 : Perspective

1.1 is a front view of a wireless charger showing our new design; 1.2 is a back view thereof; 1.3 is a left view thereof; 1.4 is a right view thereof; 1.5 is a top view thereof; 1.6 is a bottom view thereof; 1.7 is a perspective view thereof. The broken lines in the figures illustrate portions of the wireless charger that form no part of the claimed design.

1 Claim, 7 Drawing Sheets
